US0D1010300S

(12) **United States Design Patent** (10) Patent No.: **US D1,010,300 S**
(45) Date of Patent: ** Jan. 9, 2024

(54) **SHOE**

(71) Applicant: **NIKE, Inc.**, Beaverton, OR (US)

(72) Inventors: **Thomas Belhacene**, Portland, OR (US);
Earl Stewart, Portland, OR (US);
Philip Woodman, Treviso (IT)

(73) Assignee: **NIKE, Inc.**, Beaverton, OR (US)

(**) Term: **15 Years**

(21) Appl. No.: **29/689,156**

(22) Filed: **Apr. 26, 2019**

(51) LOC (14) Cl. **02-04**

(52) U.S. Cl.

USPC **D2/957**; D2/951; D2/960

CLAIM

The ornamental design for a shoe, as shown and described.

DESCRIPTION

FIG. 1 is a photographic bottom view of a shoe showing our new design;

FIG. 2 is a photographic side view thereof; and,

FIG. 3 is a photographic opposite side view thereof.

The remainder of the shoe shown in a lighter grey photographic depiction forms no part of the claimed design.

1 Claim, 3 Drawing Sheets
